UNITED STATES PATENT OFFICE.

URIAH C. GREGGS AND EDWARD H. FALLS, OF TERRE HAUTE, INDIANA.

MAIL-BOX.

1,074,713.

Specification of Letters Patent.

Patented Oct. 7, 1913.

Application filed January 10, 1913. Serial No. 741,356.

To all whom it may concern:

Be it known that we, URIAH C. GREGGS and EDWARD H. FALLS, citizens of the United States, residing at Terre Haute, in the county of Vigo, State of Indiana, have invented a new and useful Mail-Box, of which the following is a specification.

This invention relates to mail boxes such as are commonly used on rural free delivery routes wherein the box is situated at a distance from the house.

An object is to provide an alarm connected with the lid of the box whereby the occupants of a house may be notified upon the deposit of mail in the box.

A further object is to provide an alarm attachment which will sound an alarm during the opening and closing of the lid of the box.

20 Another object is to provide an ordinary push button upon the exterior of the box which may be used as an ordinary door bell alarm when the lid of the box is closed.

With the foregoing and other objects in view which will appear as the description proceeds, the invention resides in the combination and arrangement of parts and in the details of construction hereinafter described and claimed, it being understood that 30 changes in the precise embodiment of the invention herein disclosed, can be made within the scope of what is claimed, without departing from the spirit of the invention.

35 In the drawings accompanying this specification and forming a part thereof, the preferable form of our invention is illustrated, in which:

40 Figure 1 is a front view in elevation in which a portion of the body of the box has been removed. Fig. 2 represents a front view in elevation showing the exterior of the box. Fig. 3 is a diagrammatic view of the electric circuit employed.

45 Referring to the drawings in which similar reference numerals designate corresponding parts throughout the several views, 1 is the back or supporting base to which is secured a casing or mail receiving 50 receptacle comprising side walls 2 and 3, the front 4, the bottom 5 and the hinged lid 6.

55 Mounted upon the lid 6 is the finger grip 7 and mounted beneath the mail receiving casing is a resilient spring clip 8 which is

adapted to receive and retain the out-going mail. A name plate 9 has been illustrated upon the front of the box or receptacle beneath which is positioned the push button 10. The supporting back or box 1 is provided with apertures adjacent the corners thereof as indicated at 11, whereby the box may be suitably positioned upon and held to a post or other suitable support.

Secured to the hinged lid 6 is the eye bolt 65 or similar device 12 which is pivotally engaged by the link 13 of the lower extremity of which is connected to and effects a pivotal joint with the traveling arm 14 of a switch 15. The switch 15 comprises the 70 rotating or oscillating arm 14 which is adapted to travel over and effect an electrical contact with the button 16 and the button 17. The uppermost button 16 is positioned approximately centrally of the traveled arc 75 of the moving arm 14. The button 16 and arm 14 are electrically connected to a suitable alarm, such as a bell and a suitable source of electricity. The positioning of the button 16 approximately central of the traveled arc of the outer extremity of the switch arm 14 provides that the lid 6 of the mail box upon being raised for the insertion of mail in the box will sound an alarm during the opening of the said lid when the said 80 lid is approximately half way open. The alarm will again sound upon the closing of the lid and which therefore does away with the annoyance of the continuous ringing of the bell during the entire time which the lid 85 is in an open position and furthermore thereby saves a considerable amount of electric energy.

In order that the alarm circuit including the bell and battery may be used as an ordinary door bell or for similar purposes, a button 17 is positioned as the second contact of the electric switch 15 and is so positioned that the arm 14 will be in position above and in electric contact therewith during the 100 closed position of the hingedly mounted lid 6. As more clearly illustrated in the diagrammatic view in Fig. 3, the button 17 is in an electric circuit comprising the source of electric energy and the sounding alarm 105 bell. Thus when the lid is in a closed position the push button is adapted to sound the alarm and the said push button is furthermore automatically cut out of circuit upon the opening of the lid of the mail box.

In Fig. 1 the battery 18 of the dry cell type has been illustrated as being positioned within the mail receiving receptacle but it is apparent that the said battery may be located anywhere in the electric circuit.

Although the lid of the box has not been shown with any locking means, it is to be understood that the mail box may be provided with a suitable lock and furthermore 10 that a partition extends in front of and is designed to protect the switch operating mechanism, the switch itself, and the battery, provided the latter is located within the mail receiving receptacle. It is to be 15 noted in view of the foregoing that in order that the push button be connected in operative relation with the alarm it is necessary that the lid of the mail box be closed. This will furnish a suitable incentive for the closing 20 of the mail box lid should the same be left in an open condition.

Having thus fully disclosed the construction and operation of our improved mail box, what we claim to be new and original 25 with us is:—

1. A mail box comprising a mail receiving receptacle, a hinged lid therefor, a two point switch linkedly connected to said lid, one of said switch points adapted to sound 30 an electric alarm during the opening and closing of said lid, the second of said electric switch points adapted to be brought into an electric circuit including a push button, at the closure of said lid.
2. In a device of the class described, a mail box comprising a mail receiving receptacle and a hinged lid therefor, a two point contact switch disposed within said receptacle, a linked connection between the traveling 40 arm of said switch and said hinged lid, an electric circuit including a source of electric energy and a sounding alarm connected to said switch traveling arm and to the upper of said electric switch contacts, to 45 thereby sound an alarm during the opening and closing of said lid, the lower of said switch contact points electrically connected to a push button disposed on the outer por-

tion of said mail box and shunting said first mentioned contact.

3. A sounding alarm for a mail box comprising a two point switch linkedly connected to the mail box lid, one of the points being above the other, an electric circuit including a source of electric energy and a sounding alarm connected to said switch and to the upper of said electric contact points, a conductor from the lower of said electric contact points including a push button and connected to the upper point, said upper of said contact points designed to sound a limited alarm during the opening and closing of said lid, said lower contact point adapted to connect the electric push button in the alarm circuit during the period of closure of said mail box lid.

4. A sounding alarm for a mail box comprising a two point switch linkedly connected to the mail box lid, one of the contact points being above the other, the upper point of said switch disposed approximately central of the arc of travel of the traveling arm of the switch, the lower switch point disposed at the lower extremity of the arc of travel of the traveling arm of the switch, 75 an electric circuit including a source of electric energy and a sounding bell connected to said switch traveling arm and to the upper contact point, and a connection between the upper and lower switch contact 80 points including a push button, the upper contact point adapted to sound the alarm for a limited period during the opening of the lid and to sound an alarm for a limited period during the closing of said lid, and 85 said switch adapted to operatively connect said push button with said bell when the lid is in a closed position.

In testimony that we claim the foregoing as our own, we have hereto affixed our signatures in the presence of two witnesses.

URIAH C. GREGGS.
EDWARD H. FALLS.
